UNITED STATES PATENT OFFICE.

ROBERT EDWIN REARDON, OF OTTAWA, ONTARIO, CANADA.

CLOSABLE GARBAGE COLLECTOR OR STRAINER.

1,315,414.

Specification of Letters Patent. Patented Sept. 9, 1919.

Application filed September 6, 1916. Serial No. 118,638.

To all whom it may concern:

Be it known that I, ROBERT EDWIN REARDON, of the city of Ottawa, in the county of Carleton, Province of Ontario, and Dominion of Canada, have invented certain new and useful Improvements in Closable Garbage Collectors or Strainers, of which the following is a full description.

This invention relates to improvements in sink garbage collectors and strainers and particularly to such as may be used as kitchen sink strainer cartons which after use may be converted into a package of refuse or garbage, and the objects of the invention are to provide a container which may be manufactured at a low cost, which will be neat in appearance, and sanitary in use.

Further objects are to provide simple and readily operable means for closing the open top between intervals of use, in order to screen the contents from view and avoid attraction of flies, etc., and it consists essentially of the improved construction herein-after described in detail in the accompanying specification and drawings.

In the drawings,

Figure 1 is a perspective view of the container with the top closed, the open position being shown in dotted lines.

Fig. 2 is a longitudinal sectional view of the top open.

Fig. 3 is a cross sectional detail of the bottom as a container.

Fig. 4 is a plan view of the blank from which the container is formed by folding.

In the drawings like characters of reference refer to like parts in all the figures.

The strainer-carton or container may be of sheet metal but is conveniently formed of paper or pulp stock. The term paper is used to include any similar fibrous foldable material.

It is preferable to form both the body portion and the closed wings of the carton or container by folding from a single blank, this blank as shown in Fig. 4, includes a central perforated bottom portion 10, having pairs of diametrically opposite wings 11, 12, 13 and 14 formed on the sides thereof, the inner portions of the wings being adapted when folded to form the sides of the carton. The inner portions 16 and 17 of the wings 13 and 14 form the ends of the carton, while the outer portions 18 and 19 are adapted to fold downwardly to form a support for the body portion and bottom of the carton, supporting

the bottom a distance from the bottom of the sink or the like in which the carton is placed.

The outer extremity of the wings 13, and 14 are formed with extensions 21 and 22 which normally are folded up against the outer portions 18 and 19, being retained in position by means of tongues 23 which engage suitable slots 24 in the portion 19. When it is desired to convert the carton into a refuse package, the portions 21 and 22 are bent beneath the same to form a closure for the perforations in the bottom portion 10, and interlocked with each other by tongues 23 in 21 engaging the slots 25 in 22.

The wings 11 and 12 are formed with inner portions 30 and 31, which are adapted to form the sides of the carton. Between the said inner portion and the bottom 10, a plurality of folds 33 are formed designed to be bent into a flange 34 which gives additional support for the bottom 10, as shown in Fig. 3, while a portion 35 of the side extends downwardly to rest on the surface of the sink or other support on which the carton is placed.

The portions 33 are formed with tabs 36 and 37 designed to be folded across the ends and interlocked with each other by means, for example, of the tabs 38 engaging with the slots 39.

The inner portions 30 and 31 are formed on the sides with flaps 40 adapted to extend across the end portion of the wings supporting the same.

The wings 11 and 12 are formed in the outer end with extensions 44 and 45, adapted to fold over the top as shown in Fig. 1, to form a closure for the same. These extended portions of the wings are caused to move in unison with each other by means of flaps 46, which are bent laterally, the flaps on the opposite extensions being connected by pivot pins 47. In one position it will be seen that the extension 45 forms part of the side walls of the carton, while in another position they form a closure for the top of the carton. They are conveniently held in closed position by means of a tongue 50, formed in the portions 18 and 19.

It will be seen that the blank may be readily folded to form the carton. The top may be closed whenever desired to tidy up the sink in which the carton stands, and when filled with refuse the whole package may be completely inclosed and thrown away as a whole.

As many changes could be made in the

above construction and many apparently widely different embodiments of my invention within the scope of the claims constructed without departing from the spirit 5 or scope thereof, it is intended that all matter contained in the accompanying specification and drawings shall be interpreted as illustrative and not in a limiting sense.

What I claim as my invention is:

- 10 1. A carton having a body portion and a pair of diametrically opposite wings formed with integral lateral extensions, pivotally connected together adapted in one position to form a closure for the body portion.
- 15 2. A carton having a body portion with a pair of diametrically opposite wings, formed with lateral projections and pivot pins connecting the projections on opposite wings.
- 20 3. A carton having wings forming the sides thereof, the inner portions of certain of the wings being formed with a plurality of folds forming supporting flanges for the carton and interlocking tabs forming extensions of said flanges.
- 25 4. A carton formed from a folded blank

having a perforated central portion and a plurality of pairs of wings each having an inner portion forming a side of the carton and an outer portion forming a support for the carton, one pair of wings being formed 30 with extensions adapted to fold over to form a closure for the carton, the other pair of wings being formed with extensions adapted to reinforce the side of the carton.

5. A carton formed from a folded blank 35 having a perforated central portion and a plurality of pairs of wings each having an inner portion forming a side of the carton and an outer portion forming a support for the carton, one pair of wings being formed 40 with extensions adapted to fold over to form a closure for the carton and being also, formed with side flaps adapted to fold over the adjacent sides of the carton.

In witness whereof I have hereunto set 45 my hand in the presence of two witnesses.

ROBERT EDWIN REARDON.
